UNITED STATES PATENT OFFICE.

JOHN E. BLACK, OF MENDOTA, ILLINOIS.

VENEER-GLUING MACHINE.

Application filed November 23, 1925. Serial No. 70,978.

This invention has to do with improvements in veneer gluing machines and the like. The invention relates to improvements in machines for edge uniting the veneer by a direct edge gluing operation. In the past it has been customary to edge unite veneers by the use of one or more relatively thin strips of paper or the like secured along the adjoining edge portions of one or both surfaces of the veneer strips. This system has been open to numerous objections when used in certain classes of service, all of which are well known to those skilled in the art.

One object of the present invention is to provide a machine for bringing the edge portions of the veneer strips into direct, firm and even contact with each other after the adhesive has been applied, and retaining them in such contact during the setting of the adhesive.

Another object of the invention is to make provision for ensuring a perfectly uniform and even contact between the entire length of the edge portions of the veneer strips, notwithstanding any slight irregularity in the setting of the veneer strips into the machine.

Another feature of the invention relates to the provision of means for heating the edge portions of the strips while they are held in the firm contact with each other. In this connection, it is intended to make use of an adhesive having a chemical composition, such that the setting thereof is either accelerated or insured by the application of a sufficient amount of heat to bring about certain chemical changes within the adhesive itself. An action of this kind is to be distinguished from a mere drying operation induced by the application of heat. The chemical reaction referred to ordinarily necessitates the application of a temperature of approximately 170° Fah., and upon the application of this temperature the adhesive itself immediately undergoes a chemical change resulting in a "setting" or hardening. One of the objects of the invention is to apply a heating element to the joint at the proper time in the cycle of movements in order to insure the correct amount of this heating operation.

More particularly it is an object of the invention to provide a machine which shall automatically perform the various necessary operations in proper sequence, and in particular to so arrange the machine that when

the operation is started, the veneer sheets may first be positioned with their edges against a set of separating pins, thereafter the sheets will be clamped to the respective table sections, thereafter the pins will be removed from between the sheets, thereafter the table sections will be forced together under spring pressure to bring the edges of the veneer sections together, and thereafter a heating element will be applied under pressure to the edge portions of the veneer sections while held together.

Other objects and uses of the invention will appear from a detailed description of the same, which consists in the features of construction and combinations of parts hereinafter described and claimed.

In the drawings:

Fig. 1 shows a side elevation of a machine embodying the features of the present invention, portions thereof being cut away so as to better illustrate the construction of the tables and the operating mechanism;

Fig. 2 shows a plan view corresponding to Fig. 1;

Fig. 3 shows a section on the line 3—3 of Fig. 1, looking in the direction of the arrows, showing the table operating mechanism;

Fig. 4 shows a section on the line 4—4 of Fig. 1, looking in the direction of the arrows, and illustrates the mechanism for operating the heating element;

Fig. 5 shows a fragmentary section on the line 5—5 of Fig. 1, looking in the direction of the arrows, and illustrates the mechanism for operating the clamping bars;

Fig. 6 shows a fragmentary section on the line 6—6 of Fig. 1, looking in the direction of the arrows, and illustrates the mechanism for operating the spacing pins.

The machine illustrated in the drawings includes a pair of table sections 10 and 11, the table 10 being stationary and the table 11 being movable laterally towards and from the table 10. These tables are supported in any convenient manner, as, for example, by means of a pair of end brackets 12 and 13. The table section 10 is fixed to the end brackets, whereas the table section 11 is slideable back and forth. Springs 14 tend to shift the table section 11 over towards the section 10, said springs being conveniently placed between lugs 15 which reach down from the bottom of the table section 11 and a longitudinally extending channel

16 which reaches between the end brackets 12 and 13.

Embracing the adjoining edge portions of the two table sections are the clamping members 17 and 18 respectively. Each of these is preferably in the form of a hollow rectangle completely embracing the table section on which it operates. Said clamping members 17 and 18 are also preferably of 10 channel cross section, as clearly indicated in several of the figures.

Spring 19 are placed between the bottom faces of the table sections and the respective clamping members, and tend to force said 15 clamping members downward so as to press their top sections against the tables or any material carried thereby. These springs are of sufficient strength to ensure satisfactory and effective clamping of the veneer sections to the respective tables.

Reaching along below the lower portion of one or both tables is a pin bar 20, illustrated particularly in Figs. 1 and 4. A series of pins 21 reach upwardly from said bar, 25 preferably working through suitable perforations in the edge portion of the stationary table section 10. Normally this pin bar and its pins are sustained in the raised position, indicated in Figs. 1 and 4, so that 30 any veneer material placed on the table sections may be brought into definite position by bringing its edge against the pins. In the figures, I have illustrated the veneer sections 22 and 23 in place on the two tables 35 and with their adjoining edges set directly against the spacing pins 21. When so set into place, the veneer sections are accurately spaced with their adjoining edges separated exactly the desired amount and parallel to each other. These pins may be lowered 40 from between the veneer sections by depressing the bar 20.

The adjoining edges of the table sections 10 and 11 are tongued, as shown at 24 and 45 25, the overlap of said tongue portions being sufficient to ensure proper cooperation within the limits of table movement, and to thereby keep the top surfaces of the table sections in alignment.

Extending across the machine above the 50 position of the joint and above the position of the pins 21 is a bearing member in the form of a heating bar 26 positioned to bear upon the adjoined edges of the veneer sheets. This bar has on its bottom surface a suitable 55 heating element whereby its temperature may be maintained at the desired point. Preferably this heating element is in the form of electric resistance wires 27 suitably connected with a source of electric current. The bar 26 is conveniently provided 60 with downwardly reaching pins 28 and 29 at its two ends, which pins are normally operated upon by springs 30 tending to depress 65 the heating bar.

It is desired to provide mechanism for performing the following operation:

First, permitting the clamping elements 17 and 18 to be lowered into the clamping position by their springs 19; then to lower 70 the pin block 20, together with its pins 21, a sufficient distance to entirely remove said pins from between the veneer sections; then to release the movable table section 11 and allow the same to be shifted laterally by the 75 springs 14; and then to lower the heating bar 26 so as to carry its heating element against the top surface of the joint. It is desired to effect a reverse movement in the following sequence:

First, to raise the bar 26 with its heating element; then to release the clamps 17 and 18 by compressing their springs 19; then to withdraw the movable table section 11; and finally to lift the pin bar 20 with its pins 80 21, this last action preferably taking place either as a delayed operation, or, in some instances, as the first step of the next sequence of operation. In this connection, it will be noted that upon raising the pins 21, the central united portions of the veneer sheets will be raised a slight amount above the surfaces of the tables unless the veneer sheet be first removed. Owing to the relatively small amount of this lifting action, 90 it will not, in most cases, cause any damage to the joint, but in some cases, as before stated, it may be desirable to delay the raising of the pins a slight interval of time or cause them to be raised as the first step of 95 100 the next series of operations.

Any suitable mechanism may be provided for bringing about the movements above recited. In the particular construction illustrated, however, the following arrangement 105 is provided:

Extending across the machine is a main drive shaft 31, which is journaled in the end brackets 12 and 13. Rotatably mounted on 110 this shaft is a drive gear 32 which is in constant mesh with a driving pinion 33 mounted on a stub shaft 34 journaled in the bracket 12 and driven by a pulley 35.

A clutch block 36 is splined upon the shaft 115 31 having a series of clutch faces 37 on one side. These clutch faces are adapted to engage companion faces 38 on the clutch block 39 on the drive gear 32. A spring 40 tends to throw the clutch block 36 into engagement with the block 39. When this takes 120 place, a driving connection is established to drive the shaft 31.

At a position below the clutch faces there is a release pin 41 slidably mounted within 125 a bracket 42 and normally raised by a spring 43. A foot treadle 44 is pivoted at the point 45 and operatively connected to the pin 41, so that when the treadle is depressed, said pin is also lowered. The head 46 on the 130

upper end of the pin rides against a flat shoulder 47 on the side face of the clutch block 39. The clutch block 36 has its side face 48 adapted to also rest against the pin head 46. Said face 48 is provided with a cam shaped enlargement 49 which, when the clutch block 36 comes around, will ride against the pin head 46, and thus cause the block 36 to be forced sidewise and the clutch 10 disengaged. Upon depressing the foot treadle, the pin head 46 is withdrawn from the faces 47 and 48 and the clutch block 46 is then thrown into engagement with the block 39 by the spring 40. The clutch block 15 39 is rotating constantly and the shaft 31 is, therefore, picked up and turned over.

As soon as the operation commences, the operator will release the foot treadle allowing the pin head 46 to be restored to a position 20 between the faces 47 and 48. As the shaft 31 completes a revolution, the cam surface 49 will ride up onto the pin head 46 and thus throw the clutch block 36 sidewise, disengaging the clutch at the completion 25 of one revolution. It is thus evident that a one revolution clutch is provided.

On the shaft 31 are located the four cam wheels 50, 51, 52 and 53, the shapes of which are shown in Figs. 3, 4, 5 and 6. At one 30 side of the machine and at a higher elevation than the shaft 31 is another shaft 54 journaled in the brackets 12 and 13 at the points 55 and 56, respectively. This shaft 54 carries the arms 57 and 58 which are pinned 35 to the lower ends of the bars 28 and 29, respectively. A lever 59 secured to the arm 54 has a roller 60 working on the cam block 50. Consequently, the rocking of the shaft 54 is controlled by the cam 50, which, therefore, 40 controls the up and down movements of the heating element.

Journaled on the shaft 54 is a bell crank 61, the horizontal arm 62 of which carries a roller 63 at its free end, said roller 45 working on the cam block 51. The vertical arm 64 of said bell crank connects by a link 65 with the lug 15 on the bottom face of the movable table section, so that the back and forth movements of said table section are 50 controlled by the cam 51.

Swingingly mounted on the shaft 54 is another arm 66, the front end of which carries a roller 67 working on the cam block 52. This arm 66 serves primarily as a guide 55 arm. At the position of the roller 67 the arm 66 carries a yoke 68 which is connected to the lower portions of both of the clamping bars 17 and 18 by links 69 and 70, respectively. Consequently, the cam block 52 60 controls the movements of the clamping bars.

There is another lever 71 also swingingly mounted on the shaft 54, said lever serving primarily as a guide arm. At its free end 65 this lever carries a roller 72 working on the

cam block 53; and a yoke 73 is also connected to the arm 71 at the position of the roller. This yoke reaches up and is connected to the pin bar 20. Consequently, the movements of said pin bar are controlled 70 by the cam block 53. Reference to Figs. 3, 4, 5 and 6 will show the relative shapes of the cam blocks. Rotation of the cam blocks is counterclockwise, as indicated by the arrows in said figures. Comparison of 75 the various cam blocks will show that the first operation is the clamping of the clamps 17 and 18, due to the riding of the roller 67 over the shoulder 74 of the cam block 52.

The next operation is the riding of the 80 roller 72 over the shoulder 75 of the cam block 53 which results in the lowering of the spacing pins from between the veneer sheets. The next movement is the riding of the 85 roller 63 over the shoulder 76 of the cam block 51 resulting in the lateral shifting of the table section 11 to bring the edges of the veneer sheets together. The next operation is the riding of the roller 60 over the shoulder 77 of the cam block 50 resulting in 90 the lowering of the heating element.

The next operation is the riding of the 95 roller 60 onto the shoulder 78 of the cam block 50 resulting in raising the heating element; the next operation is the riding 100 of the roller 67 onto the shoulder 79 of the cam block 52 resulting in releasing the clamping bars; the next operation is the riding of the roller 72 onto the shoulder 80 of the cam block 53 resulting in raising the 105 spacing pins; and the next operation is the riding of the roller 63 onto the shoulder 81 of the cam block resulting in the separating movement of the table section 11.

Examination of Fig. 3 shows that the 110 heating element is retained in the lowered position during the movement between the shoulders 77 and 78. This interval should be sufficient to ensure proper chemical action due to the application of the heating 115 element. As previously stated, the glue or adhesive is preferably one which undergoes a chemical change to the application of heat, as distinguished from a merely drying action. Such a glue, which is well known in 120 the art, comprises dried black blood albumin, one hundred parts by weight; distilled water, one hundred eighty parts by weight; slacked lime, five parts by weight; and ammonium hydroxide, six parts by weight.

To prepare this glue, mix the water and the albumin, stirring gently, and allow to stand several hours. Then stir in the ammonium hydroxide. Add the lime just before using, the same having been previously 125 dissolved in twice its weight in water. This glue is given merely by way of illustration and is not intended as a limitation on the practice of the features of the present invention.

While I have herein shown and described only a single embodiment of the features of my present invention, still I do not intend to limit myself to the same, except as I may 55 do so in the claims.

I claim:

1. A machine of the class described, including in combination a pair of supports for veneer sheets lying in substantially the 10 same plane, at least one of which supports is shiftable towards and from the other, a vertically movable veneer spacing device adjacent to the edges of said supports, means for clamping veneer material on each support, and a vertically movable heating device substantially in line with the adjacent edges of the supports, 15 together with means for forcing the clamping means into co-operative relationship with the supports, for removing the spacing device from between the veneer sheets, for shifting the movable support laterally to 20 carry the edges of the veneer material together, and for forcing the heating device into engagement with the edge portions of the veneer material, substantially as described.

2. A machine of the class described, including in combination a pair of supports for veneer sheets located adjacent to each other and relatively shiftable one towards and from the other, a vertically movable veneer spacing device adjacent to the edges 30 of said supports, means for clamping veneer material on each support, and a vertically movable heating device substantially in line with the adjacent edges of the supports, together with means for forcing the clamping 35 means into co-operative relationship with the supports, thereafter removing the spacing device from between the veneer sheets, thereafter shifting the movable support laterally to carry the edges of the veneer material together, thereafter forcing the heating device into engagement with the edge portions of the veneer material, and thereafter disengaging the heating device and the clamping devices, substantially as described.

3. A machine of the class described, including in combination a pair of supports for veneer sheets located adjacent to each other and relatively shiftable one towards 40

and from the other, a vertically movable veneer spacing device adjacent to the edges of said supports, means for clamping veneer material on each support, and a vertically movable heating device substantially in line with the adjacent edges of the supports, 50 together with means for forcing the clamping means into co-operative relationship with the supports, for removing the spacing device from between the veneer sheets, for shifting the movable support laterally to 55 carry the edges of the veneer material together, and for forcing the heating device into engagement with the edge portions of the veneer material, substantially as described.

4. A machine for joining sheet material, having a holding device for independently clamping each of the sheets and comprising press bars and means for moving the said press bars together with the sheet between them one towards the other, a pressing element intermediate the said press bars adapted to move at right angles to the latter movement of the press bars, and means to move said pressing element subsequently to 70 the movement of the press bars.

5. A machine for joining sheet material, having a holding device for independently clamping each of the sheets and comprising press bars and means for moving the said press bars with the sheet between them one towards the other, a pressing element intermediate the said press bars adapted to move at right angles to the latter movement of the press bars, means to heat the said pressing element, and means to move said pressing element subsequently to the movement of the press bars.

6. A machine for joining veneers and having in combination abutment members for the correct alignment of the sheets introduced, a holding device comprising movable press bars, a pressing jack between the said pressing bars and consisting of an upper and a lower member, a main shaft, and means upon the said main shaft independently to move the pressing bars, the pressing jack and the abutment members, the latter movement being established after the clamping of the veneers between the press bars and 100 prior to their lateral movement.

JOHN E. BLACK.
